UNITED STATES PATENT OFFICE

ROGER ADAMS, OF URBANA, ILLINOIS, ASSIGNOR TO ABBOTT LABORATORIES, OF
NORTH CHICAGO, ILLINOIS, A CORPORATION OF ILLINOIS

POLYHYDRIC ALCOHOL ESTER OF ALIPHATIC CARBOXYLIC ACIDS

No Drawing.

Application filed January 21, 1931. Serial No. 510,287.

The invention relates broadly to bactericides and has particularly to do with a group of substances which are especially applicable as bactericides and bacteriostatic agents in combating acid-fast bacteria. The invention covered in this application may be considered an improvement over that set forth and claimed in my co-pending application on Bactericides applicable to acid-fast bacteria, Serial No. 329,077, filed December 28, 1928.

Chaulmoogra oil, *hydnocarpus wightiana* oil and related oils as well as chaulmoogric acid, and homologues of chaulmoogric acid and their derivatives have long been known to be effective in combating certain diseases such as leprosy, produced by acid-fast bacteria. The activity against the leper bacilli of all these products has generally been attributed to the presence of the chaulmoogric acid or a homologue. Recent discoveries have shown that a variety of other acids which contain other types of carbon rings are also effective against such acid-fast bacteria.

Further discoveries seem to demonstrate that a ring structure is not necessary but that the number of carbon atoms, the molecular weight of the compounds, and the position of the carboxyl group in the chain are important factors in determining the bactericidal and bacteriostatic efficiency of the products. Acids or derivatives of acids containing more than 11 and less than 21 carbon atoms appear to be most efficient, particularly those containing 15 to 18 carbon atoms. The presence or absence of a ring structure seems to be of minor importance.

As set forth in my co-pending application above referred to, I have found surprisingly high bactericidal and bacteriostatic efficiency in certain aliphatic acids and their derivatives in which the carboxyl group is removed from the end of the chain, and that frequently the efficiency is noticeably increased as the carboxyl group is placed nearer the center. The highest efficiency seems to reside in those compounds wherein said group is attached to the middle carbon atom or to a carbon atom that is near the middle of the molecule.

The present application relates to poly-

hydric alcohol esters of acids which may be represented by the general formula $RCH(COOH)R'$, where R and R' are alkyl groups containing one or more carbon atoms and where the sum of the carbon atoms contained in $R+R'$ in any single acid will total not less than 12 nor more than 21 carbon atoms. The most effective esters are those wherein the acids present contain a total of 15 to 18 carbon atoms. Two of the most common polyhydric alcohols are ethylene glycol and glycerol, and these substances are two of the most desirable of such alcohols for my purpose.

The esters covered by the previous statement are essentially synthetic oils corresponding very closely to natural oils. These particular ones can be used in place of chaulmoogra oil or the oil of *hydnocarpus wightiana* or others of a similar character in the treatment of leprosy.

The substances covered in this application are somewhat less irritating than the products specifically referred to in my said co-pending application. Hence, larger quantities thereof may be injected into the human organism.

Example

256 g. of di-heptyl acetic acid (3 mole equivalents) and 31 g. (1 mole equivalent) of glycerol are heated together in a round-bottomed flask fitted with a condenser set for distillation, whereby the water which is obtained by heating the mixture may distill. The temperature of the bath is held at 225-235° C. After heating about nine hours no more water is eliminated and the reaction is stopped. The reaction mixture is very dark brown and sometimes almost black.

The mixture is cooled and a 2-cc. sample is titrated with 0.1 N sodium hydroxide solution. To the main portion is then added sufficient 5 per cent sodium hydroxide solution in an amount equivalent to 20 per cent more than is sufficient to neutralize the free acid present. The mixture is then stirred vigorously for three hours at 100° and allowed to settle for another hour. Two layers separate, the bottom one containing the soap

and impurities, the top the light-brown glyceride. The latter is washed four times with equal volumes of hot water and the last time is allowed to settle for one to two hours. The water is drawn off and the oil dried by heating to 120-140° in vacuo for two to three hours. The resulting glyceride cannot be distilled under any ordinary conditions without decomposition.

- 10 By this same procedure, the ethylene glycidles and glycerides of the following acids were prepared: di-n-pentyl acetic acid, n-butyl-n-hexyl acetic acid, n-butyl-n-heptyl acetic acid, n-hexyl-n-amyl acetic acid, di-n-15 hexyl acetic acid, n-butyl-n-octyl acetic acid, n-hexyl-n-heptyl acetic acid, n-butyl-n-nonyl acetic acid, di-n-heptyl acetic acid, n-lauryl ethyl acetic acid, n-propyl-n-undecyl acetic acid, n-heptyl-n-octyl acetic acid, di-n-octyl 20 acetic acid, n-nonyl-n-heptyl acetic acid, n-heptyl-n-decyl acetic acid, n-hexyl-n-undecyl acetic acid, di-n-nonyl acetic acid and n-heptyl-lauryl acetic acid.

All of these substances are obtained in the 25 form of thick oils, brownish in color, odorless and essentially tasteless. They are readily converted by the action of aqueous or alcoholic alkalies into glycol or glycerol and the salts of the corresponding aliphatic acids.

30 Various modifications and improvements coming within the spirit of my invention will doubtless occur to those skilled in the art. Hence, I do not wish to be limited to the specific embodiments described or uses mentioned except as set forth in the appended claims, which are to be interpreted as broadly as the state of the art will permit.

I claim as my invention:

40

105

1. As a new composition of matter, especially useful as a bactericidal or bacteriostatic agent, a polyhydric alcohol ester of $RCH(COOH)R'$, where R and R' are alkyl groups containing a total of not less than 70 12 or more than 20 carbon atoms.

2. As a new composition of matter, especially useful as a bactericidal or bacteriostatic agent, a polyhydric alcohol ester of $RCH(COOH)R'$, where R and R' are alkyl 75 groups containing a total of not less than 15 or more than 18 carbon atoms.

3. As a new composition of matter, especially useful as a bactericidal or bacteriostatic agent, an ethylene glycolide of 80 $RCH(COOH)R'$, where R and R' are alkyl groups containing a total of not less than 12 or more than 20 carbon atoms.

4. As a new composition of matter, especially useful as a bactericidal or bacteriostatic agent, an ethylene glycolide of 85 $RCH(COOH)R'$, where R and R' are alkyl groups containing a total of not less than 15 or more than 18 carbon atoms.

5. As a new composition of matter, especially useful as a bactericidal or bacteriostatic agent, a glyceride of $RCH(COOH)R'$, where R and R' are alkyl groups containing a total of not less than 90 12 or more than 20 carbon atoms.

6. As a new composition of matter, especially useful as a bactericidal or bacteriostatic agent, a glyceride of $RCH(COOH)R'$, where R and R' are alkyl groups containing a total of not less than 95 15 or more than 18 carbon atoms.

ROGER ADAMS.
